CHARLES N. HAYES, OF ROCHESTER, NEW YORK.

NON-REFILLABLE BOTTLE.

1,167,754.

Specification of Letters Patent. Patented Jan. 11, 1916.

Application filed August 24, 1915. Serial No. 47,053.

To all whom it may concern:

Be it known that I, CHARLES N. HAYES, of Rochester, in the county of Monroe and State of New York, have invented a new and useful Non-Refillable Bottle, fully set forth in the following specification and shown in the accompanying drawings.

The present invention relates to non-refillable bottles, and an object of the same is to provide a construction without any sharp bends which will interfere with the free flowing of the liquid from the bottle.

Another object of the invention is to provide a construction which is sensitive in its action and acts to close the valve if the bottle neck be shifted to a horizontal position or above the same.

To these and other ends, the invention consists in certain parts and combinations of parts all of which will be hereinafter described, the novel features being pointed out in the appended claims.

In the drawings: Figure 1 is a view of portions of the neck of a bottle with parts thereof shown in section and interior parts shown in elevation: Fig. 2 is a vertical section through the bottle neck when the latter is upright; Fig. 3 is a view similar to Fig. 2 showing the positions of the parts when the bottle is arranged horizontally; Fig. 4 is a like section showing the bottle in discharging position; and Fig. 5 is a horizontal section through the bottle neck above the valve.

In the illustrated embodiment of the invention, 1 indicates a portion of the neck of a bottle which is in one piece with a bottle body (not shown). This neck portion has a cork or other resilient washer 2 abutting its upper end and a neck portion 3 separate from the portion 1 abuts the opposite face of the washer 2. Preferably, the neck portion 3 is held to the neck portion 1 by an open ended sleeve 4 made of sheet metal and bent inwardly at 5 to engage with an annular shoulder 6 on the neck portion 3. At its other end, this open ended sleeve 4 is formed with pressed screw threads 7 engaged with a mutilated screw 8 formed on the neck portion 1, the sleeve being bent inwardly at 9 into the mutilated portion of the thread 8 to hold the sleeve against rotation on the neck portion 1. A shoulder valve seat 10 in the form of a ring is fitted concentrically within the washer.

The neck portion 3 preferably has a cylindrical inner bore 11 throughout the

greater portion of the length thereof, and at its extreme end, a reduced cylindrical bore 12 is provided for receiving the cork or stopper 13. Between this cylindrical bore 12 and the cylindrical bore 11, a tapering or curved shoulder or abutment 14 is provided and within the chamber formed between the valve seat 10 and the abutment 14, a valve 15 operates, said valve being preferably in the form of an inverted cup-shaped member resting upon the valve seat and having radial ribs 16 which provide between them passageways for the liquid. The upper face of this valve 15 is flat and is engaged by the flattened face 17 of a weight 18 the latter being of a tapering form or a truncated cone-shape.

Above the weight 18, a weight 19 is arranged, the latter having, in its bottom, a pocket 20 formed with cylindrical walls and fitting over the tapered portion of the weight 18. The lower portion of this weight 19 is of cylindrical formation while the upper portion tapers at 21. Both portions are formed with longitudinally extending ribs 22 which conform to the shape of the weight, the tapering portion of the ribs being adapted for co-operation with the curved abutment 14 as will be hereinafter described.

The operation of the invention is as follows: The bottle is filled before the separable neck portion 3 is fitted thereto, after which the neck portion 3 with the valve parts therein is attached to the neck portion 1 by turning a sleeve 4 until a liquid tight joint is secured between the two neck portions, the yielding washer 2 permitting the obtaining of such joint. Thereafter, the sleeve 4 is pressed inwardly at 9 to hold the sleeve against surreptitious removal except by the distortion of said sleeve. A cork or stopper introduced into the mouth of the bottle will engage the upper weight 19 and hold the latter together with the weight 18 and the valve 15 against movement so that the liquid cannot pass into the neck portion 3. When the bottle is to be used, the stopper 13 is removed and the bottle turned to the position shown in Fig. 4, the valve 15 moving from its seat and the weights 18 and 19 being received respectively in the pocket 20 of weight 19 and the tapered portion 14 of the bottle neck, thereby permitting a free flow of the liquid about these parts without any sudden or sharp turns in the liquid.

If the bottle be moved to a horizontal position, the valve 15 is immediately closed, stopping the flow, this being due to the fact that the weight 19 will rock on its upper 5 end as a bearing to swing its pocketed end laterally and, in this way, impart a movement to the weight 18. The latter in turn, by reason of its tapered walls, moves toward the valve 15 and also laterally toward the 10 interior cylindrical wall of the neck, thus acting on the valve 15 to move the latter toward its seat. The valve is firmly held in this position due to the fact that the weight 18 continuously exerts pressure on the valve 15 as it does not touch the inner side wall of the bottle neck but is held suspended between the weight 19 and the valve 15. Both 15 the weight 18 and the weight 19 may be made of leaded glass to give them sufficient weight 20 for the performance of their functions.

A non-refillable bottle constructed in accordance with this invention is inexpensive to manufacture because the bottle neck does not have any projections or shoulders which 25 are difficult to form but, instead, is smooth throughout its length, and the weights and valve are also of simple construction. The parts coöperate in such a manner that a free flow of the liquid from the bottle is possible 30 while, should the bottle be held in a position to fill the same, the valve will immediately close. The introduction of devices into the neck of the bottle for the purpose of preventing the closing action of the valve tends 35 to close the valve.

What I claim as my invention and desire to secure by Letters Patent is:

1. A non-refillable bottle having a neck, a seat in the neck, a valve arranged to coöperate with the seat to close the neck and having a flat face, a member arranged in the neck above the valve and having a pocket in the under side thereof and a weight having a substantially flat face portion to coöperate 40 with the flat face of the valve, and a tapered portion received within the pocket of the pocketed member, the pocket being of a size to permit the end of the tapered portion 45

to shift laterally therein while the weight is 50 tilting on an edge of the pocket as a fulcrum to close the valve.

2. A non-refillable bottle having a neck, a seat in the neck, a valve arranged to coöperate with the seat to close the neck, and having a flat top face, a member arranged in the neck above the valve and having a pocket arranged in its under side, and a weight having a flat face to coöperate with the flat face of the valve and a tapered portion operating in the pocket and arranged to 60 tilt on one edge of the pocket as a fulcrum.

3. A non-refillable bottle having a neck, a seat in the neck, a valve having a flat top face and arranged to coöperate with the seat to close the neck, two weights arranged in 65 the neck above the valve, one of said weights having a pocket in its under side and the other of said weights having a flat face for coöperation with the flat face of the valve and a tapered portion operating in the pocket 70 of the first named weight, said pocket being of a size to permit the end of the tapered portion to shift laterally therein while maintaining the greater portion of the weight outside of the pocket at all times, so that the 75 weight may tilt laterally on the edge of the pocket as a fulcrum to close the valve.

4. A non-refillable bottle comprising a neck, a seat in the neck, a valve arranged to coöperate with the seat to close the neck and having a flat-top face, a fixed abutment in the neck, and two weights one of which acts 80 on the fixed abutment to rock laterally, and has a pocket in its under side, said pocket having substantially cylindrical side walls, 85 and the other of which has a flat face for co-operation with the flat face of the valve and a tapered portion projecting within the pocket of the first named weight while maintaining the greater portion of the weight 90 outside of the pocket at all times so that the second named weight may tilt on the edge of the pocket as a fulcrum to engage the valve and close the same.

CHARLES N. HAYES.
